UNITED STATES PATENT OFFICE.

MARY ELIZABETH KNIVETON, OF PHOENIX, ARIZONA TERRITORY.

CURTAIN-DRAPERY CLAMP.

SPECIFICATION forming part of Letters Patent No. 788,649, dated May 2, 1905.

Application filed December 8, 1904. Serial No. 236,066.

To all whom it may concern:

Be it known that I, MARY ELIZABETH KNIVETON, of Phoenix, in the county of Maricopa and Territory of Arizona, have invented 5 a new and Improved Curtain-Draping Clamp, of which the following is a full, clear, and exact description.

My invention relates to improvements in that class of devices intended for use in holding window-curtains, portières, and the like in a desired position.

The object of my invention is to produce a cheap and simple spring-acting clamp which can be conveniently applied to the casing of 15 a window or door and which will serve to hold a curtain, portière, or other fabric in a desired position.

My invention is especially intended to provide a simple spring-acting means for holding 20 the curtain in such a way that it will not be mussed, its folds will be maintained, and the desired effect or design produced.

My invention is also intended to act in such a way as to enable the curtain to be instantly 25 slipped into position and to hold it in such a manner that if accidentally pulled out no injury will be done to either the curtain or the fixture.

My invention is also intended to utilize the 30 bend which gives the spring action to the clamping-tongue for taking care of any surplus goods which it may be necessary to hold in the device.

With these ends in view my invention consists of a curtain-draping clamp, the construction 35 and operation of which will be herein-after described and the novel features claimed.

Reference is to be had to the accompanying drawings, forming a part of this specification, 40 in which similar letters and figures of reference indicate corresponding parts in all the views.

Figure 1 is an elevation of a pair of window-curtains, one of which hangs normal and 45 the other of which is held in my improved device. Fig. 2 is an enlarged detail plan of the device as applied to a support, and Fig. 3 is a perspective view of the clamp.

The device is made, preferably, of wire hav-

ing a certain amount of spring action and a 50 single piece is bent to the desired shape. It has a base formed of the members 10, the wire at one end of one member being formed into an eye 11 to receive a fastening-screw or equivalent fastening, and the two members are united by 55 the bend 12. The second member 10 is bent at the end to form the laterally-extending brace 13, and the wire is here twisted to form a second eye 14 to receive the fastening-screw or equivalent. After being formed into the second eye 14 the wire extends backward essentially parallel with the members 10 and is again bent inward at 16, so that the parts 10, 15, and 16 lie flat upon the support and form a secure base for the device. The wire is again bent 60 at 17 and formed into the loop 18, after which the wire is returned upon itself and bent at 19 to form the terminal tongue 20, which fits between the two members 10 and lies snugly enough to grip a curtain or other fabric which is inserted behind the tongue, the binding effect being increased because the fabric is doubled in between the two members 10. The tongue 20 terminates at its free end in a finger-hold 21, the wire being bent to ring shape 65 at this end, and while forming a finger-hold it also serves to round the end of the tongue, so that it cannot injure the fabric when the latter is pushed into the clamp between the parts 70 10 and 20.

In applying the device to a window or door a clamp is fixed to the casing on each side, as shown at A in Fig. 1, with the opening next the curtain. The curtain is then looped up to the desired extent and simply pulled into the clamp which grips the fabric, as shown. It will be readily seen that any desired combination effect can be produced—that is, that the curtain can be folded or looped in the particular manner preferred and easily held 85 in this way by the clamp. It will be further seen that if the curtain should be pulled suddenly or blown hard by the wind it will without tearing free itself from the clamp. It will be noticed also that the part 18, while 90 affording the necessary spring action to the tongue 20, provides also for receiving any surplus goods which may be forced into the clamp. 95

Having thus fully described my invention, I claim as new and desire to secure by Letters Patent—

1. A device of the kind described comprising a spring-clamp formed of a single piece of wire having a looped base with parallel members, said wire being formed into screw-eyes at the adjacent ends of the parallel members, the wire continuing from one of said eyes and forming a loop and extending to form a terminal spring-tongue fitting between the parallel members.
2. A device of the kind described comprising

ing a spring-clamp formed of a single piece of wire having a looped base with parallel members, screw-eyes formed at the adjacent ends of the parallel members, the wire extending from one of the said eyes to form a loop having a spring-tongue fitting between the parallel members, and a loop formed at the end of the spring-tongue.

MARY ELIZABETH KNIVETON.
